United States Patent Office.

ELIJAH MELTON, OF FLEMINGSBURG, KENTUCKY.

Letters Patent No. 104,977, dated July 5, 1870.

IMPROVEMENT IN MECHANICAL MOVEMENTS.

The Schedule referred to in these Letters Patent and making part of the same.

To all whom it may concern:

Be it known that I, ELIJAH MELTON, of Flemingsburg, in the county of Fleming and State of Kentucky, have invented a new and improved Mechanical Movement; and I do hereby declare that the following is a full, clear, and exact description of the construction and operation of the same, reference being had to the accompanying drawing making a part of this specification, in which—

Figure 1 is a plan view, and

Figure 2, a side elevation.

This invention consists in an apparatus for communicating motion from a motor-shaft to a driving-shaft through the agency of an intermediate system of leverage, instead of by direct circumferential contact of the wheels.

In the drawing—

A is a wheel, placed on the motor-shaft A'.

B is the driving-shaft, bearing a fly, B', on one end, and a toothed pinion, b, at the other end.

C is the supporting frame-work, which sustains, in addition to the shaft A' and the shaft B, two shafts, C C', additional to the latter one at each side of it, at equal intervals, and in the same horizontal plane.

The shafts C C' bear pinions, c c', which gear with the pinion b.

D is a lever, having its fulcrum in a standard, D', vertically over the central shaft B, and just out of the vertical plane of the pinions b c c'.

The lever is joined by a rod, d, with a pin projecting from the wheel A at a point of the latter not central.

It is likewise joined by rods d' d'', with pins similarly placed in the outer pinions c c'.

The motion of the wheel A is communicated to the lever D through the rod d, and from the lever D to the pinions c c', through the rods d' d'', and from the pinions c c' to the driving-shaft B, through the pinion b.

This arrangement gives the advantage of the compound-lever in the turning of a shaft.

Having thus described my invention,

What I claim as new, and desire to secure by Letters Patent, is—

The wheel A, pinions b c c', connecting-rods d d'', and lever D, combined and arranged substantially as described.

To the above specification of my improvement I have set my hand this 28th day of October, 1869.
